(57) CLAIM

I claim the ornamental design for a sports shoe, as shown and described.

DESCRIPTION

FIG. 1 is a top planar view of a sports shoe showing my new design;

FIG. 2 is a side view thereof;

FIG. 3 is an opposite side view thereof;

FIG. 4 is a rear view thereof;

FIG. 5 is a front view thereof;

FIG. 6 is a rear perspective view thereof; and,

FIG. 7 is another perspective view.

The broken lines in the figures show features of the sports shoe that form no part of the claimed design.
